UNITED STATES PATENT OFFICE.

WICENTY DROZDZ, OF CLEVELAND, OHIO, ASSIGNOR OF ONE-HALF TO EUGENE BOROWSKI, OF CLEVELAND, OHIO.

FLOOR SCRUBBING AND MOPPING MACHINE.

1,384,124.

Specification of Letters Patent. Patented July 12, 1921.

Application filed December 12, 1919. Serial No. 344,334.

To all whom it may concern:

Be it known that I, WICENTY DROZDZ, a subject of the Government of Poland, residing at Cleveland, in the county of Cuyahoga 5 and State of Ohio, have invented certain new and useful Improvements in Floor Scrubbing and Mopping Machines, of which the following is a specification.

This invention relates to a floor scrubbing 10 machine and has for its object to provide a simple, effective and novel means for efficiently scrubbing the floor and is particularly adapted for use in places where large floor areas are to be cleaned.

15 Further objects of the invention are in providing an improved and simplified construction so designed as to insure a better cleaning of the floor surface by reason of the peculiar arrangement of parts embodied 20 therein and the provision of means for mopping the dirty water from the floor after the scrubbing brush has thoroughly cleaned the same and the provision of separate reservoirs for the used and unused cleaning fluid.

25 Further objects of the invention are in part obvious and will appear in part more clearly from the following description and claim.

In the accompanying drawings Figure 1 30 is a central longitudinal section of the machine. Fig. 2 is a cross section on the line 2—2 of Fig. 1. Fig. 3 is a similar section on the line 3—3 of Fig. 1.

The machine consists of a rectangular 35 casing 1 provided at its rearward end with an inclosed housing 2 extending upwardly therefrom and in which are housed the mopping and wringing attachments. Directly in front of the housing 2 and securely 40 mounted to the top of the casing 1 are reservoirs 3 and 4, the reservoir 3 being provided for the carrying of the unused cleaning fluid, and the reservoir 4 for the used fluid. The bottom of the reservoir 3 discharges 45 through a valve 5 into a tube 6 which extends laterally across the front edge of the casing 1 and said tube is provided with a plurality of apertures 7 thereby to spray the cleaning fluid upon the floor directly in 50 front of the machine.

The foregoing parts are mounted upon a pair of traction wheels 8, said traction wheels being carried by a shaft 9 which extends through and has bearing in the side 55 walls in the casing 1 and said shaft has

mounted upon one side thereof and inside of the casing a large spur gear 10 which has meshing therewith a spur gear 11 mounted upon a crank shaft 12. The scrubbing brush 13, slidably mounted within guideways 14, has connection with the crank shaft 12 by means of a connecting link 15. Thus a rotary movement of the traction wheels 8 imparts a reciprocating movement to the scrubbing brush 13. It is at times desirable 60 to impart greater pressure upon the floor through the scrubbing brush and it is therefore necessary to make the brush adjustable. Means therefor consist of securing the guideways 14 pivotally through a link 16 65 with a bracket 17 carried by the top of the housing. The forward part of the guideways carries a finger 18 which projects through a slot 19 in the front wall of the casing. One side of said slot is provided 70 with notches 20 which are engaged by the finger 18 to hold the scrubbing brush 13 at the desired height.

Also secured upon the shaft 9 is a sprocket wheel 21 which drives a roller 23 through a 75 chain 22, and said roller is mounted in suitable bearings carried by the casing 1 and has mounted thereon a mop in the form of a belt 24. This belt may be of any bibulous material and the top portion thereof is 80 passed over a roller 25. A third roller 26 carried by the casing bears against the belt 24 in such a manner as to exert a wringing effect thereon and the fluid so drawn from the belt is caused to flow into the reservoir 85 4 by means of an apron 27. Access may be had to the wringing belt through a hinged cover 28 upon the top of the housing 2 and the belt may be conveniently replaced by removing the lower roller shaft through a 90 split bearing 30. A squeegee 31 is secured to the rearward lower edge of the housing 2 to thoroughly dry up all the water. By providing handles 33 the device may be conveniently pushed upon the floor and by the 95 provision of an outlet nozzle (not shown) the reservoir may be drained at any time.

In constructing the device it is preferable to make the body portion of the machine of sheet metal and other working parts thereof 100 which come in contact at any time with cleaning fluid, of a material which will be unaffected thereby, and while I have shown and described this particular arrangement and combination of parts it is evident that 110

various modifications may be employed for effecting a like result and I do not wish to limit myself in the construction of the same further than is required by the state of the 5 art or that which comes within the scope of the appended claim.

I claim:

In a scrubbing machine, the combination of a wheeled casing having a slot in the 10 front wall thereof, a guide in the casing, having a handle at its front end projecting through said slot, whereby said guide may

be swung up or down, means to hold said guide in adjusted position, links pivoted to the side walls of the casing and secured to 15 the rear end of said guide, a brush reciprocating in said guide, and means to reciprocate the brush.

In testimony whereof, I do affix my signature in presence of two witnesses.

WICENTY DROZDZ.

Witnesses:

EUGENIUS BOROWSKI,
JOHN A. BOMMHARDT.
